(57) **CLAIM**

The ornamental design for a convertible table and easel, as shown and described.

DESCRIPTION

FIG. 1 is a front view of an embodiment of a convertible table and easel showing my new design in a storage position; FIG. 2 is a rear view of the design of FIG. 1 shown in the storage position;

FIG. 3 is a front and right side perspective view of the design of FIGS. 1 and 2 shown in an easel position;

FIG. 4 is a rear and left side perspective view of the design of FIGS. 1-3 shown in the easel position;

FIG. 5 is a left side view of the design of FIGS. 1-4 shown in the easel position;

FIG. 6 is a right side view of the design of FIGS. 1-5 shown in the easel position;

FIG. 7 is a top view of the design of FIGS. 1-6 shown in the easel position;

FIG. 8 is a bottom view of the design of FIGS. 1-7 shown in the easel position;

FIG. 9 is a front view of the design of FIGS. 1-8 shown in the easel position;

FIG. 10 is a rear view of the design of FIGS. 1-9 shown in the easel position;

FIG. 11 is a front and left side perspective view of the design of FIGS. 1-10 shown in the table position;

FIG. 12 is a front and right side perspective view of the design of FIGS. 1-11 shown in the table position;

FIG. 13 is a left side view of the design of FIGS. 1-12 shown in the table position;

FIG. 14 is a right side view of the design of FIGS. 1-13 shown in the table position;

FIG. 15 is a bottom view of the design of FIGS. 1-14 shown in the table position;

FIG. 16 is a top view of the design of FIGS. 1-15 shown in the table position;

FIG. 17 is a front view of the design of FIGS. 1-16 shown in the table position; and,

FIG. 18 is a rear view of the design of FIGS. 1-17 shown in the table position.
